UNITED STATES PATENT OFFICE

2,072,290

AUTOMATIC EJECTING FUSE

Heinz P. Bauman, Detroit, Mich.

Application May 5, 1936, Serial No. 78,044

1 Claim. (Cl. 200—130)

This invention appertains to new and useful improvements in fuses and more particularly to a novel device wherein the fuse is ejected automatically.

5 The principal object of the present invention is to provide a device in the form of an automatic fuse which when blown results in the automatic ejection of the whole fuse cap, thus indicating immediately to the attendant which of a group of 10 fuses has blown.

Other important objects and advantages of the invention will become apparent to the reader of the following specification.

In the drawings:—
15 Figure 1 represents a side elevational view of the device.

Figure 2 is a longitudinal sectional view.

Figure 3 is an end elevational view of the plug portion of the structure.

20 Figure 4 is a section on the line 4—4 of Figure 3.

Figure 5 is an end elevational view of the cap portion of the fuse.

Figure 6 is a section on the line 6—6 of Figure 5.

25 Figure 7 is a perspective view of the fusible element.

Referring to the drawings wherein like numerals designate like parts, it can be seen that numeral 5 generally refers to the plug section of the fuse, while numeral 6 generally refers to the cap section of the fuse.

The plug section 5 consists of a body 7 of insulation having the thread formed annulus 8 thereon. At one end of the body 7 is the insulation plate or disk 9 in which the contact 10 is mounted.

Extending into the body 7 from the opposite end thereof are the pockets 11—11 in which the U-shaped spring contacts 12 are mounted, one of which is connected with the thread-formed conductor annulus 8 and the other with the contact 10.

The cap section 6 includes the body 13 of insulation and in this body the contact prongs 14 are suitably anchored and allowed to project a

substantial distance beyond one side of the cap so as to engage into the U-shaped spring contact 12 of the plug section 5. The cap 13 is formed with a pocket 15 from the back wall of which projects the stub 16 around which the coiled compressible spring 17 is disposed with one end impinging against the back wall of the pocket 15. The opposite end of the spring bears against the circular intermediate portion 18 of the fusible element 19 which is secured by soldering, welding 10 or other method or means at its end to the contact prongs 14—14. The fusible element 19 has the flanges 20—20 around the free edge portion of the central portion 18 thereof to assist in properly guiding or retaining the spring 17. 15

It can now be seen that with the sections 5—6 assembled in the manner shown in Figure 2, any rupture of the fuse 19 will free the spring 17 and it will exert its tension against the fuse and against the section 5, thus throwing the entire cap 13 away from the plug section 7. Thus at a glance, an attendant can tell which one in a group of fuses is blown. 20

While the foregoing specification sets forth the invention in specific terms, it is to be understood that numerous changes in the shape, size and materials may be resorted to without departing from the spirit and scope of the invention as claimed hereinafter. 25

Having thus described the invention what is claimed is:—

A fuse plug of the character described comprising a plug section, a cap section, said plug section being provided with pockets, contacts in the pockets, contact prongs on the cap section adapted to engage into the pockets and with the contact in the said pockets, a fusible element connected at its end to the contact prongs, and a coiled compressible spring interposed between the cap and the fuse normally held compressed by said fusible element, said fusible element having a circular central portion provided with a peripheral flange within the confines of which one end convolution of the spring is normally located. 35 40 45
